SETON J. ALLEN, OF VINELAND, NEW JERSEY.

LAST FOR MAKING SHOES.

Application filed December 16, 1926. Serial No. 155,318.

My invention relates to lasts for making shoes, and more particularly to lasts which may be used for the manufacture of shoes that will most perfectly accommodate the 5 normal or abnormal formation of the foot, with particular reference to the formation of the foot sole.

In the heretofore known art, lasts have been made so that a shoe may be formed 10 thereon, such that it might be approximately accommodated and worn by a deformed foot.

It is my purpose to make a last by means 15 of which a shoe may be formed for general wear, so that it will most accurately and hygienically support the foot of the usual and ordinary wearer, and so that there may be obtained the greatest ease and comfort of movement, as well as the greatest ease 20 and comfort when the wearer is not moving.

It is further my purpose to create a last 25 upon which a shoe may be built that will most perfectly conform to the normal formation of the sole of the foot.

30 I do not intend by this invention to create a device by which an abnormally formed foot may be correctly supported, but I do intend that a last, as hereafter described, shall be such that a shoe built thereon will be of the character and design which will anatomically, properly, and correctly conform to the normal formation of the sole 35 of the foot and will properly and most comfortably, as well as most normally support the wearer.

In the prior art it is known that various types of lasts have been made upon which shoes have been built that have supported the arch of the foot.

40 It is well recognized that these types of lasts and shoes are usually built for abnormally formed feet.

It is to be understood, therefore, that although I term this last one upon which an 45 orthopedic shoe may be built, I therefore do not wish to be understood as having devised a last which is particularly applicable to feet of abnormal formation, but as having devised a last upon which shoes may be 50 built that will fit and comfortably support, most normally, feet both of normal and abnormal formation, within certain limits, the limitation being particularly in reference to feet of abnormal formation.

One of the objects of my invention is, to 55 provide a last by means of which, in the course of manufacture, a shoe may be constructed, which will provide the most comfort to the wearer and which will give to the wearer the most proper poise and balance, in 60 order that the walking movement may be accomplished with the greatest ease, and in order that the wearer, when not walking, may stand with the most complete comfort.

Another object is to provide a last of such 65 construction that a person wearing a shoe built thereon, will, if defects be inherent in the feet of the wearer, have them approximately corrected, as the result of the formation of the shoe; the correction of 70 these defects being a result particularly of the formation of the arch, or intermediate portion, of the inner-sole of the shoe built from the last which is the subject of this application.

75 My invention consists of the particular combination, organization and formation of parts shown in the accompanying drawing, described in the specification and more specifically pointed out in the appended claims.

In the drawings:

Fig. 1 is a bottom plan view of my last, showing the formation and location of the recessed portion thereof, by means of which I effect the particular desired formation of 85 the innersole of the shoe built on the last as shown.

Fig. 2 is a longitudinal cross-section, on line 2—2 of Figure 1, showing the formation of the last, the depression in the arch portion thereof and the approximate depth of such depression.

Fig. 3 is a view taken as Figure 2, but showing an exaggerated depression of the depressed portion of the last.

Fig. 4 is a side elevation of the last, showing the position and degree of depression of the depressed section, near the ball of the foot.

Fig. 5 is a diagonal section taken on line 100 5—5, showing the curvature of the depressed portion of my last.

Fig. 6 is a transverse section taken on line 6—6 of Figure 1, showing the transverse curvature at that point of my last, and particularly the indentation therein.

Fig. 7 is a perspective view looking in the direction of the arrow, and partially in

cross-section, of the sole of my last, particularly showing the curvature toward the inner portion of the foot of the intended portion in the last; illustrating the twist in the indented portion, which I consider necessary to the formation of this type of last.

Fig. 8 is a perspective view of my last, taken from the rear, with particular reference to the curvature of the indented portion thereof, and with further reference to a convex raised portion as shown near the heel.

Referring to the drawings, in which like numerals of reference indicate corresponding parts, my last comprises a forward or toe portion 10, and a heel portion 11, of substantially usual shape and formation, but my last comprises also an intermediate portion between the portions 10 and 11 which is commonly called the arch portion.

It is within this arch portion that my invention particularly lies.

I have found that the normal shape of the sole of the foot under this intermediate portion, between the portions 10 and 11 on my last, is such that it should be supported by an elevated section within the inner sole of the shoe; in order to give the correct support to that portion of the foot which in the shoes as heretofore made was not properly supported.

In order to accomplish this effect, I have so formed my last that in this intermediate section between the toe portion 10 and the heel portion 11, I provide an indented or depressed section 12.

This indented or depressed section 12 is somewhat pear-shaped and extends, as illustrated in Figure 1, from the line 13—13, which is substantially the line determining the point of the ball of the foot as normally formed, as to its forward position, to the line 6—6, which is the line which determines the normal point of raise of a normal heel in the normal foot.

I have illustrated in Figure 1 a last upon which a shoe for the right foot may be built. It is in reference to this that the further description of the drawing, so far as this figure is concerned, will be made.

The formation of the depressed portion 12 is such that there is on the outer side of the last a lifted or undepressed section 14, extending substantially from the ball of the small toe to the lift which begins the heel of the foot; increasing in width from the outside border of the last as it progresses rearwardly and terminating at, or substantially at, the line 6—6, indicating a cross sectional cut in Figure 1.

Likewise the configuration of this depressed portion is, at its forward or toe end of the last, substantially that conforming to the shape of a pear, having one side flattened, being that side adjacent to the outer portion of the last, and having the other

side enlarged, being that side adjacent to the inner portion of the last.

Respecting the contour of the indented portion of the last, namely,—the portion 17 which is opposite the portion 14 above described, it will be seen this portion 17 recedes rearwardly from the enlarged portion of the front 16 of the depressed section in a concaved linear formation. This formation is such that substantially the intermediate point of this formation describes the deepest concavity, and is also at this point substantially midway of the arch of the foot.

The depressed section 12, which forms within the last the lifted or undepressed section 14 on the outer side of the last, will be seen to be bounded by the line 16^a and will be seen to terminate both as to the lifted portion 14 and depressed section 12 at the line 6—6 upon which a cross section has been made and heretofore described.

Respecting the portion 17 it will be seen that it terminates at its rearward end on the line 6—6 as does the portion 14 bounded by the line 16^a.

The portion 17, defined by the line 17^a is, beside being on the base of the last, inset laterally from the inner longitudinal face of the last, particularly at that portion which is inset or concaved at the arch, so that my last is formed at that section with an inwardly receding roll, which extends laterally but which is formed as to its longitudinal length in a line which extends from the ball of the foot or big toe to the heel. This line 17^a so defines the curvature of the formation on the inner side of the last, which contains this inset or indented portion 12, that it limits both the width and the length of this indented portion from the portion 16, so that it will provide means upon which an inner-sole for a shoe may be built or moulded, to conform to the normal configuration of the foot sole.

I have shown in Figure 2, a sectional view taken on line 2—2 of Figure 1 of the construction of my last; and therein I have shown the depression 12 in cross-section which is illustrated in Figure 1 in plan view.

In Figure 3 I have illustrated a partial forward section of my last, showing the depressed section 12 as exaggerated in depth. This figure being but a partial cross-sectional view of the toe portion of the last, but with the heel portion removed.

In Figure 4 I have shown a side elevation of my last which illustrates, not only the formation of the toe portion 10 and the heel portion 11, but the formation and extent of the indented portion 12 and which also, by the dotted line 12^b and the full line 12^a, shows the twist in the curvature of the indented portion 12.

In order to more fully comprehend the shape and formation of this indented portion on the bottom of my last, I have illustrated in Figure 6 a view which would appear in cross-section from a cut on line 6-6, Fig. 1, looking in the direction of the arrow.

I have also shown in Figure 5 in order to indicate the formation and curvature of the 10 depressed section 12, a cross-sectional view taken on line 5-5 of Figure 1, looking in the direction of the arrow.

In Figure 7 it will be seen that I have shown not only the particular formation of 15 the depressed or indented section 12 in my last as to its depth, but have also indicated the fact that it has a somewhat spiral twist or curvature, which is more depressed at the inner side of the last than at the outer, 20 and which substantially merges with the line of formation of the inner side of the last at 17* and which leaves a substantial ridge or roll such as 14 in Figure 1 on the outer side which roll or elevated section 14 25 substantially terminates in its rearward extension at the line 6-6 marking the point where the cross-section of Figure 6 has been taken, as shown in Figure 1.

It will be noticed from Figure 7, that on 30 the inner side of this concaved or depressed portion 12 near the cross-sectional intersection line 6-6 there is substantially a lump or elevated section or portion 18 which terminates the rearward extent of the depressed portion 12 of my last.

It will also be observed that on or near 35 the outer side of the last, and particularly the portion which determines the inner margin of the section 14, there is a raised or elevated section 19.

These elevated sections 18 and 19 co-ordinating with the twisted formation of my 40 depressed last section 12 are of such shape and so disposed that they enable me to build thereon a shoe having an inner-sole which 45 is of such formation that it conforms to the natural formation of the foot sole, and to form a shoe which will have a substantial tendency to reform an ordinarily deformed 50 foot capable of wearing such a shoe, and which as well will comfortably fit the normal foot.

Attention is particularly called to the fact 55 that there is a specified location for this depressed section of the last, and that the applicant believes that this particular location as specified is the only correct location by means of which the wearer of a shoe built upon such a last may have the most complete comfort.

It will be noticed from Figure 8, that 60 the last which applicant is seeking to patent is particularly designated by the following characteristics, which are as follows:—That on the outer side of this last

there is a bulge and that this bulge extends from the front rearwardly toward the heel on the outer side at the arch portion and that there separates the outer portion of the outer side of this last from the indented 70 last arch section.

It will be observed also that, on the inner side of the sole of the last that the formation will be such that the inner sole will conform to the formation of the foot and 75 will approximately line up with the ordinary and usual formation of the outer sole,—as seen in Figures 7 and 8.

It will be seen, therefore, that I have provided a last upon which may be built a 80 shoe which will accommodate not only the ordinary type of foot, but which will correct the formation of the type of foot which may be incorrectly formed from natural or accidental causes.

Therefore, although I have thus described 85 my invention in detail and illustrated it in the accompanying drawings, I do not wish to be limited to the particular form or shape or disposition of the shape of my invention 90 by the terms which may describe it; for it is obvious that various modifications may be made in the combination, organization, arrangement and formation of parts which embody my invention, without departing 95 from the spirit and scope thereof.

Claims:

1. A shoe last, having a longitudinally extending, transversely curved and twisted depressed surface in the arch portion of its 100 bottom face, extending from the heel portion to the ball of the toe portion, the forward and intermediate portions of said depressed arch portion surface being concavely curved and tapering toward the heel portion, the portion of said arch portion adjacent said heel portion being slightly convexly curved.

2. A shoe last, having a longitudinally extending, transversely curved and twisted 110 depressed surface in the arch portion of its bottom face, extending from the heel portion to the ball of the toe portion, and merging at its forward end into a transversely curved line near the ball of the foot, 115 and at its ends merging into oppositely curved lines, which merge into the lateral curvature of the above mentioned arch, said arch surface being concavely curved in its forward and intermediate portions, and convexly curved on opposite sides adjacent its heel portion.

3. A last for shoes, comprising a body portion, having a heel section, and a forward or toe section, said last being characterized by an indented concavity provided in the sole of the toe portion, said concavity extending from the ball portion of said last rearwardly to the heel portion, and extending laterally from one side of said 125 130

- last and terminating near the opposite side of said last, there providing a relatively elevated marginal section in the body of the last sole that determines the boundary of said concavity on one side, said concavity being located approximately under the arch of the foot and being formed with a spiral twist inclined downwardly at the inner side of said last.
- 10 4. A last for shoes, comprising a body portion, having a toe section, and a heel section, said last being characterized by a depressed portion provided on the sole of the toe portion thereof, said depressed portion extending longitudinally from the ball of the foot approximately to the heel, and laterally extending partially across the sole of the last under the arch portion of the foot, and being formed with a spirally twisted curvature, more depressed on the inner side of the last than on the opposite side, said concavity being adapted to permit the moulding on said last of an inner sole of a shoe, to produce thereon a convex, spirally curved, raised portion, so formed that the latter will perfectly conform to and effectually support the arch of a foot.
- 15 5. A last for shoes comprising a body portion, having a toe section, and a heel section, and having a depressed, concavely
- shaped, spirally twisted indented portion, formed in the toe section of said last, said indented section extending from one margin of the sole of said last to near the opposite margin, forming at said opposite margin an 25 undepressed section of the last, said concavely formed indented portion being adapted for the moulding of inner soles of a shoe thereon to give the latter a formation such that it will correctly fit the foot of a wearer. 40
6. A last for shoes comprising a toe portion, and a heel portion, having a depressed, concavely formed section in the sole of the toe portion, said concavely formed section extending from the inner side of said last 45 to near the outer side of said last, being more deeply depressed at the inner side than at the outer side of said last and terminating near the heel in substantially convexly formed lifted sections, which are positioned approximately at the opposite sides of said last near the heel portion thereof, the forward end of said depressed concave section terminating approximately at the ball of the foot and the entire depressed section 50 extending entirely under the arch of the foot.

In testimony whereof I have hereunto set my hand.

SETON J. ALLEN.
